UNITED STATES PATENT OFFICE.

CARL RABE, OF SANGERHÄUSEN, PRUSSIA, GERMANY, ASSIGNOR TO THE SANGERHÄUSER ACTIEN - MASCHINEN - FABRIK AND EISENGIESSEREI, VORM. HORNUNG & RABE, OF SAME PLACE.

SUGAR-CANE-SLICING MACHINE.

SPECIFICATION forming part of Letters Patent No. 398,348, dated February 19, 1889.

Application filed March 16, 1887. Serial No. 231,147. (No model.)

To all whom it may concern:

Be it known that I, CARL RABE, of the city of Sangerhausen, in the Kingdom of Prussia and German Empire, have invented a certain 5 new and useful Improvement in Sugar-Cane-Slicing Machines, of which the following is a specification, reference being had to the accompanying drawings, and to the letters of reference marked thereon.

10 This invention relates to those sugar-cane-cutting machines which have feed-hoppers inclined to the vertical axis of the cutting-disk for so presenting the cane slantwise to the cutters that it is divided into approximately el- 15 liptical slices obliquely to the length of the cane.

The object of my invention is to improve the construction of the rotary cutting-disk, and provide novel means for severing the 20 canes into slices of varying thickness. The object I accomplish by the construction and combination of devices hereinafter described and claimed, reference being made to the accompanying drawings, in which—

25 Figure 1 is a vertical sectional view of the machine embodying my invention; Fig. 2, a top plan view; Fig. 3, a side elevation; Fig. 4, a sectional view of the cutting-disk, taken on the line $y-y$, Fig. 5; Fig. 5, a broken plan view 30 showing a portion of the cutting-disk; Fig. 6, a side view of part of a sugar-cane, showing the oblique line on which it is sliced; Fig. 7, a detail plan view of a slice of the cane and in the direction of the line $z-z$; Fig. 8, a sectional view of the cutting-disk on the line $w-w$, Fig. 5.

In order to enable those skilled in the art to make and use my invention, I will now describe the same in detail, referring to the drawings, 40 wherein—

The letter b indicates a suitable frame, having at its upper end a receptacle, d , surmounted by a cover-plate, d' , provided with rectangular openings, from which extend the 45 feed-hoppers i . These hoppers are placed in inclined positions relatively to the vertical shaft a , which carries the cutting-disk e at a point directly under the cover-plate, so that

the cutters o will travel in close proximity to the lower open ends of the feed-hoppers.

The shaft a is rotated by bevel gears c c' , shaft a^2 , and pulley a^3 thereupon, all substantially as shown in English Patent No. 14,402 of 1884.

The inclined feed-hoppers are open at their upper ends to receive the canes u , which at their lower ends rest upon the cutting-disk e . In order that the canes will regularly descend the inclined wall of the feed-hopper, and to insure constant contact of the canes with the cutting-disk, I provide each feed-hopper i with a transverse slot, i' , in its inner wall, and provide rollers k , journaled in bearings i^2 on the outside of the hoppers in such manner that a portion of the periphery of each roller will project through one of the slots i' slightly into the hopper and afford a rolling rest for the canes. By the inclination of the feed-hoppers the tendency of the canes u is to bear upon the disk e , but by the rollers this is insured, while at the same time the canes will regularly and uniformly descend upon the cutting-disk.

The disk e is provided with a series of radial slots, e' , extending from near its hub to near its periphery, there being at the peripheral portions of the disk the recesses, as at e^2 , so that the reduced outer ends or tenons, h' , of the cutter-carrying boxes h enter said recesses and engage under the peripheral portions of the disk, Figs. 1 and 8. The disk e at the sides of each slot or opening e' is provided with radial bars n , which project inwardly and serve as rests for the boxes h when the latter are inserted into said slots or openings. The 75 radial bars n are detachably secured to the under side of the disk by screws n' , passing through the bars and tapped into the disk, Figs. 4 and 5.

The cutters or blades o are connected with 90 one side of the boxes h by screws o' , while on the opposite sides of the boxes are arranged movable counter-pieces p' , which can be adjusted vertically in relation to the cutting-edges of the cutters through the medium of 95 set-screws m in the boxes directly under the

counter-pieces. By this means the distances between the cutting-edges of the counter-pieces can be varied at will to cut the cane into slices of any desired thickness. By entering the outer reduced ends or tenons h' into the correspondingly-shaped recesses e^2 , and thus engaging such reduced ends under the outer edges of the disk e at the outer ends of the slots e' , the boxes are firmly held down in proper position and also prevented from outward sliding movement without the use of extraneous fastening devices.

The sugar-canies u , when introduced into the feed-hoppers, will bear at their lower ends against the disk e , and rest at their under sides against the periphery of the rollers k , and the latter will yield, or, rather, roll, under the least downward tension of the canes, and thereby insure the desired regular and uniform downward feed motion. The slices u' , severed by the cutters o , are approximately elliptical in form and fall upon the horizontal bottom wall of the chamber d , from whence they are carried to the discharge-spout g , through the medium of radial blades f^4 , secured to the sleeve f^5 , which is loosely mounted on the shaft a . This sleeve is rotated at less speed than the cutting-disk and shaft a by means of pinions f, f', f^2 , and f^3 of different diameters. The small pinion f is fixed to the shaft a , and rotates the largest pinion f' on a secondary shaft, f^6 , which is thus revolved at less speed than the shaft a . The shaft f^6 also carries a small pinion, f^2 , which drives a larger pinion, f^3 , on the sleeve f^5 , whereby the circumferential speed of the sleeve is still slower than

shaft f^6 , and the blades f^4 are thus revolved at a low speed compared to the speed of the cutting-disk.

I do not confine myself to any particular number of feed-hoppers or cutter-boxes and cutters, as these may be varied at will.

Having thus described my invention, what I claim is—

1. The combination, with a frame having a chamber provided with a covering-plate and a feed-hopper delivering the cane through said plate, of the rotary disk e , having a radial slot, e' , and a recess, e^2 , at the under side of the periphery of the disk communicating with the slot, the side bars, n , the boxes h , carrying a cutter, o , resting on the side bars and having an outer reduced end or tenon, h' , entering the said recess and engaging under the peripheral portion of the disk, substantially as described.

2. The combination of the cutting-disk e , having a radial slot, e' , and a recess, e^2 , under the peripheral portion communicating with the slot, with the cutter-carrying box h , having a reduced outer end or tenon, h' , entering said recess and engaging under the peripheral portion of the disk, substantially as described.

In testimony whereof I have signed my name to this specification in the presence of two subscribing witnesses.

CARL RABE.
